E. S. BLACK.
TWO-PART DIPPER FOR EXCAVATING MACHINES.
APPLICATION FILED FEB. 17, 1912.

Patented Aug. 18, 1914.

UNITED STATES PATENT OFFICE.

EDWARD S. BLACK, OF CHICAGO, ILLINOIS, ASSIGNOR TO EDGAR ALLEN AMERICAN MANGANESE STEEL COMPANY, OF AUGUSTA, MAINE, A CORPORATION OF MAINE.

TWO-PART DIPPER FOR EXCAVATING-MACHINES.

1,107,252.

Specification of Letters Patent. Patented Aug. 18, 1914.

Application filed February 17, 1912. Serial No. 678,199.

To all whom it may concern:

Be it known that I, EDWARD S. BLACK, a citizen of the United States, and a resident of Chicago, in the county of Cook and State of Illinois, have made and invented 5 certain new and useful Improvements in Two-Part Dippers for Excavating-Machines, of which the following is a specification.

10 My invention relates to dippers for excavating, dredging, digging and similar machines, and particularly to that type or form of dipper in which the body portion is made up of two parts each formed preferably from cast metal and in a single piece, and each part comprising substantially one-half of the dipper body, said parts being secured together to thereby form a two-part dipper body along joints located in the sides 15 thereof.

20 The object of my invention is to provide an arrangement of lifting ears through which the dipper is lifted by means of a suitable yoke or bail, in which the rivets or bolts whereby the ears are secured to the dipper body are relieved from shearing action; and to provide an arrangement in which the strains produced in digging do not produce shearing action upon the rivets 25 or bolts whereby the two parts of the dipper body are secured together.

20 More specifically stated, the objects of my invention are to provide a dipper body of the type above referred to in which the ears whereby the dipper is lifted when in use are located upon and secured to the front portion of the dipper body, preferably in an inclined position; and to provide a dipper body in which lugs or equivalent means are 40 provided against which the ears abut, said lugs being also preferably located upon and formed integrally with the front portion of the dipper body, whereby force transmitted through the lifting ears to the dipper in digging acts against the lugs, which lugs, being 45 located upon the same part of the dipper as that to which the ears are secured, relieves the rivets whereby the ears are secured in place from shearing action to an extent not

secured in cases where the lugs may move 50 away from the ear when the dipper is in use, as is the case when the ears are secured to one and the lugs formed upon the other part of a two-part dipper body.

With the above and other objects of invention in view, my invention consists in the improved dipper hereinafter described and claimed, and illustrated in the drawings accompanying and forming a part of this application; and in such modifications thereof as will be obvious to those skilled in the art to which my invention relates.

Referring to the drawing wherein the preferred embodiment of my invention is illustrated; Figure 1 is a view showing one 65 form of my improved two-part dipper in perspective; and, Fig. 2 is a view also in perspective showing another form of my improved construction.

Referring to the drawing, 3 is the rear 70 portion, and 4 the front portion of a two-part dipper body, these parts being formed each as a single integral casting preferably from manganese steel in order to secure excessive strength and durability for the dipper body. The rear portion 3 is provided 75 with lugs 5, 6 to the former of which suitable directing mechanism is secured, while the latter serves as a hinge connection through which the bottom 7 of the dipper is 80 pivotally supported, the details of this hinge connection not being disclosed; as they form no part of my invention.

The reference character 8 designates a detachable lip secured to the upper edge of 85 the front portion of the dipper body, 9 designates a plurality of tooth supporting shanks secured to the said front portion, and 10 designates detachable points secured to the supports 9 in a manner well understood 90 by those skilled in the art to which my invention relates, the upper ends of the shanks 9 lying in recesses 22 formed in the lip 8 in order to prevent sidewise movement of the teeth. The front and rear portions of the 95 dipper body are secured together along vertically extending joints 11 located in the sides of the dipper body about midway be-

tween the front and rear faces thereof, the front portion being preferably provided with a flange 12 which overlies the front edge of the rear portion of the dipper, and the parts being secured together by suitable fastening means such as rivets 13.

The reference character 14 designates a suitable ear, two such ears being provided one located upon each side of the dipper adjacent the upper edge thereof. The ears are formed with offset portions 15, and with a transverse shoulder 16, connecting the offset portion with the base of the ear. These ears are commonly secured to the front portion of the dipper body and the shoulder 16 therefore abuts against a projecting lug 17 located upon and preferably formed integrally with that portion of the dipper to which the ears are secured. The offset portion 15 of the ear is provided with a hole 18 at its upper end, and 19 is a hole extending through the lug 17, and the front edge of the rear portion of the dipper, and through which holes a suitable pin extends when the dipper is in use; it being understood that the dipper body as a whole when in use, is lifted by means of a suitable bail or yoke the lower ends of which are pivotally connected with the dipper body through the ears above referred to by means of pins passing through the holes 19, the lower ends of the yoke and the holes 18 in the ears. The ears 14 are preferably secured to the dipper body in an inclined position, although the degree of inclination is a matter of secondary importance.

In the form of my invention shown in Fig. 2, ribs 21 are provided which extend along each side of the base of the ear 14, the said ribs and the lug 17 together providing a pocket or recess in which the base of the ear fits whereby a more effective protection against shearing action of the rivets 20 is obtained.

From the above it will be seen that as the lifting ears and the lugs against which they abut are upon one and the same part of the dipper body, the stresses produced in digging are transmitted directly to the lugs, and not through the joint between the two parts of the body, as is the case when the ears are secured to one part and the lugs located upon the other; from which it follows that the rivets whereby the ears are secured in place are relieved from shearing stresses to an extent not possible in cases where the ears are not made to abut against a lug located upon the same part of the dipper as that to which the ears are secured. The location of the ears and lugs upon the front part of the dipper in addition to the advantages above referred to secures an application of the lifting force nearer to the front face of the dipper where the greatest resistance is en-

countered when the dipper is in use, and also serves to relieve the rivets whereby the front and rear portions of the body are secured together from shearing stresses as will be hereinafter explained, and the inclined arrangement of the ears secures an application of the lifting force more nearly in line with the resistance encountered when the dipper is in use.

In a two-part dipper body formed in accordance with my invention, the lifting ears being secured in place upon the front portion of the dipper body, the strains due to digging are not transmitted to any considerable extent through the joints between the front and rear portions of the dipper, as is the case when the lifting ears are secured to the rear portion of the dipper body, from which it follows that the rivets along the joints in question are relieved from shearing action; whereas when the lifting ears are secured to the rear portion of the dipper body, the strain due to digging, acting as it does at the front edge of the dipper, tends to tip the front portion about a fulcrum at the lower ends of the joints, thus subjecting the rivets along the joints to excessive shearing action, this shearing action being especially severe at the upper ends of the joints. This advantage is quite independent of the lugs referred to, and follows from the location of the lifting ears upon the front portion of a two-part dipper body; although it will be understood that if the lifting ears are secured to one part of the dipper body and abut against lugs upon the other, forces transmitted through the ears act not only to shear the rivets whereby they are secured in place, but also act against the lugs as fixed fulcrums and tend to force the two parts of the body apart and to introduce additional stresses tending to shear the rivets whereby the two parts are secured together.

In the specific embodiment of my invention illustrated in the drawing, it will be understood that when the dipper is in use force is transmitted through the ears 14 to the projecting lugs 17, and that the lugs cannot under any circumstances be forced from the position they occupy relative to the ears, as would be the case if the lugs in question were formed upon the rear half of the dipper body. It therefore follows that strains to which the dipper is subjected when in use are transmitted at all times through the ears directly to the lugs, and that the rivets 20 whereby the base portions of the lugs are secured to the front portion of the dipper are at all times relieved from shearing action. It will also be obvious that force applied to the lifting yoke when the dipper is in use can under no circumstances be transmitted to the rivets 13 whereby the front and rear portions of the dipper body are se-

cured together, as would be the case if the ears abutted against lugs upon the rear portion of the dipper body, and that the force applied through the yoke to lift the dipper 5 acts upon the front portion of the body only, and can under no circumstances be transmitted through the rivets whereby the two parts are secured together to the rear portion of the body. It therefore follows that in my improved construction of dipper, the rivets whereby the ears through which the dipper is lifted are secured to the dipper body are protected from shearing strains; and that the rivets whereby the 10 front and rear portions of the body are secured together are also relieved from shearing strains due to the mere act of lifting the body, or due to the action of the lifting ears upon the lugs as fulcrums.

Having thus described and explained my invention, I claim and desire to secure by Letters Patent.

1. In a dipper for excavating and similar machines, a dipper body comprising front and rear portions formed from cast metal and secured together along joints located in the sides thereof to thereby form a two-part dipper body, and each of which portions comprises approximately one-half of said body; two lifting ears located one upon each side of the body and secured to the front portion only thereof; two lugs formed integrally with the front portion of the body and against which said ears abut; and means 35 for securing said several parts together.

2. In a dipper for excavating and similar machines, a dipper body comprising front and rear portions secured together along joints located in the sides thereof to thereby form a two-part dipper body, and each of which portions comprises approximately one-half of said body; two lifting ears located one upon each side of the body and secured to the front portion only thereof; two lugs upon the front portion of the body and against which said ears abut; and means 40 for securing said several parts together.

3. In a dipper for excavating and similar machines, a dipper body comprising front and rear portions secured together along joints located in the sides thereof to thereby form a two-part dipper body, and each of which portions comprises approximately one-half of said body; two lifting ears located one upon each side of the body and secured to the front portion only thereof; projecting elements formed integrally with the front portion of the body and against which said ears abut, whereby movement of 55 said ears is prevented, and means for securing said several parts together.

4. In a dipper for excavating and similar machines, a dipper body comprising front and rear portions formed from cast metal

and secured together along joints located in 65 the sides thereof to thereby form a two-part dipper body, and each of which portions comprises approximately one-half of said body; two lifting ears located one upon each side of the body and entirely upon the front portion thereof; fastening means for securing said ears in place; means independent of said fastening means located upon the front portion of said body for preventing movement of said ears; and means for securing the front and rear portions of said body together.

5. In a dipper for excavating and similar machines, a dipper body comprising front and rear portions secured together along 80 joints located in the sides thereof to thereby form a two-part dipper body, and each of which portions comprises approximately one-half of said body; two lifting ears located one upon each side of the body and secured to one only of the portions thereof; two lugs upon that portion of the body to which said ears are secured, and against which said ears abut; and means for securing 85 said several parts together.

6. In a dipper for excavating and similar machines, a dipper body comprising front and rear portions formed from cast metal secured together along joints located in the sides thereof to thereby form a two-part 95 dipper body, and each of which portions comprises approximately one-half of said body; two lifting ears located one upon each side of the body and secured to one only of the portions thereof; two lugs formed integrally with that portion of the body to which 100 said ears are secured, and against which said ears abut; and means for securing said several parts together.

7. In a dipper for excavating and similar machines, a dipper body comprising front and rear portions secured together along joints located in the sides thereof to thereby form a two-part dipper body, and each of which portions comprises approximately one-half of said body; two lifting ears located one upon each side of the body and secured to the front portion only thereof; lugs upon the front portion of said body and against which said ears abut; and means for 110 securing said several parts together.

8. A dipper body having a separately formed front portion secured thereto along joints located in the sides of said body; two lifting ears located one upon each side of 120 said body and secured to the front portion only thereof; two lugs located one adjacent to the upper ends of each of said ears and against which said ears abut; and means for securing said several parts together.

9. In a dipper for excavating and similar machines, a dipper body comprising front and rear portions secured together along

points located in the sides thereof; two lifting ears located one upon each side of the body and secured to the front portion only thereof; lugs upon the front portion of said body and against which said ears abut; and means for securing said several parts together.

Signed at Chicago, in the county of Cook, and State of Illinois, this 12th day of February, A. D. 1912.
